UNITED STATES PATENT OFFICE.

JOHN M. HANSEN, OF PITTSBURG, PENNSYLVANIA.

LOW-SIDE GONDOLA CAR.

SPECIFICATION forming part of Letters Patent No. 727,619, dated May 12, 1903.

Application filed May 28, 1902. Serial No. 109,277. (No model.)

To all whom it may concern:

Be it known that I, JOHN M. HANSEN, a resident of Pittsburg, in the county of Allegheny and State of Pennsylvania, have invented a new and useful Improvement in Low-Side Gondola Cars; and I do hereby declare the following to be a full, clear, and exact description thereof.

My invention relates to metallic underframes for railway-cars, and more especially to underframes for cars provided with a flat bottom or floor.

The object of my invention is to improve metallic car-underframes in details of construction, which will be hereinafter described and claimed.

In the accompanying drawings, Figure 1 is a plan view of one-half of the car, the lower portion of said figure showing the floor-plates removed. Fig. 2 is a longitudinal section through the car on the line 2 2, Fig. 1. Fig. 3 is a transverse section through the bolster. Fig. 4 is a transverse section on the line 4 4, Fig. 1; and Fig. 5 on the right-hand portion 25 is a transverse section on the line 5 5, Fig. 1, and on the left-hand portion is an end view of the car.

I have shown my underframe applied to a gondola car having low sides; but it will be understood that the underframe can be used with any car having a flat bottom. The car shown is of the type having center sills, but having no side sills, the sides of the car being formed as plate-girders, which assist in supporting the load. The center sills 1 are channel-shaped structures, preferably rolled channel-beams, as shown, and are placed with their flanges preferably projecting outwardly. These center sills project beyond the body-bolsters 2 and have connected thereto outside of the body-bolsters the draft-sills 3, which extend to the end sills 4. The sides of the car are formed of metal plates 5, which extend, preferably, continuously from body-bolster to body-bolster, as shown, and other plates 6, which extend from the body-bolsters to the ends of the car. The plates 5 and 6 lie in the same plane, and their meeting edges are united by means of the trough-shaped stakes 7, having outwardly-projecting flanges to which the plates 5 and 6 are riveted. Inside of the plates opposite the stakes are

cover plates or welts 8, which reinforce the joint and exclude the lading from the trough of the stakes. The side plates are stiffened by means of angle-rails 9 and 10, riveted, respectively, to the top and bottom edges of said plates. These angle-rails are shown as having their vertical flanges lying inside of the side plates and their horizontal flanges projecting outwardly; but their vertical flanges may lie inside or outside of the side plates, and their horizontal flanges may project either inwardly or outwardly, as desired. The stakes 7 lie between the upper and lower flanges of these angle-rails, and the side plates are stiffened at intervals by sections of angle-bars 11, riveted to the outer face and extending between the flanges of the top and bottom angle-rails. The side plates, together with the top and bottom angle-rails and stiffening-angles 11, form, in effect, plate-girders, which assist in supporting the load. Stake-pockets 12 are secured at intervals to the side plates on the inside of the car.

The body-bolsters comprise top or tension members 15 and bottom or compression members 16 and web-filers 17. The top members or "cover-plates," as I term them, extend through slots 18, cut in the webs of the center sills, and extend nearly, but not quite, out to the sides of the car. The bottom or compression members 16 are in the form of plates and extend continuously underneath the center sills, nearly out the end of the bolster. The web-filers 17 are composed of two channel-shaped members formed, preferably, of pressed metal, having flanges on their upper and lower sides and inner ends, said members being placed back to back, as shown, and united by means of the top and bottom plates 15 and 16, which are riveted to the flanges of the members 17. The flanges on the inner ends of these channel members are riveted to the center sills. At their outer ends the channel members are somewhat offset or spread apart, as shown in Fig. 1, and in the space thus formed are located two of the flanges of two angle-bars 21, the other flanges of said bars projecting outwardly at 22 and serving as a convenient means for securing the sides of the cars thereto. The inwardly-projecting flanges of the angle-bars 21 are secured between the members 17 by means

of rivets, and the other flanges of said angle-bars are secured to the sides of the car by the same rivets which secure the side plates to the flanges of the stakes 7. In place of the two angle-bars 21 a single T-bar may be used. Extension-plates 23 are riveted to the lower flanges of the web-filters beyond the ends of the compression member 16 and project outwardly beyond the end of the bolster and form brackets upon which the angle-rails 10 rest and to which they are secured. Between the center sills, in line with the web-filters 17, is a brace 24, preferably formed of cast metal and riveted to the center sills, as shown, this brace being provided with a boss 25, having a vertical opening for receiving the center pin. The body-bolsters are of less depth than the center sills, and sections of Z-bars 27 are secured to the bolsters, preferably by one of the rows of rivets which secures the top cover-plate 15 to the web-filters 17, these Z-bars serving as supports for the side floor-plates 28. The floor-plates have their outside edges turned upward to form flanges which are riveted to the side plates of the car, and their inner edges are riveted to the upper flanges of the center sills. Central cover or floor plates 29 overlap the side floor-plates 28 and are riveted to the center sills. The floor-plates are supported at intervals by transoms or diaphragms 30, which are formed of sections of channel-bar and are secured to the center sills and side plates of the car by angle-pieces 32. Between the center sills, opposite some of the diaphragms 30, are braces 33, which likewise are formed of sections of channel-bar and secured to the center sills by angle-pieces 34. At the center of the car the underframe is tied together by diaphragms, which comprise sections of channel-bar 37, connected to the center sills and sides of the car by angle-pieces 38 and continuous transverse tie members 39, extending underneath the center sills from side to side of the car. These tie members 39 are connected to the channel members 37 by means of one or more web-plates 40, four such plates being shown on each side of the car, although a greater or lesser number may be employed, as necessary, or, if desired, a single continuous plate might extend from the center sills to the side of the car. The tie members 39 are shown as angle-bars having their horizontal flanges bearing against the bottom of the center sills and their vertical flanges having the web-plates 40 secured thereto. These angle-bars 39 project beyond the sides of the car and form brackets 41 for supporting the sides of the car. Between the center sills, opposite the diaphragms 37, are braces 42, formed of a plate sheared to shape and having a flange formed at its upper edge, which supports the floor-plates. This brace-plate is connected to the center sills by angle-pieces 43, and its lower edge projects downwardly, as at 44, below the center sills and is riveted to

the vertical flange of the angle-bar 39. The knee-pieces 44 on the opposite edges of the brace 42 lie on opposite sides thereof, as shown in Fig. 1, the object of this being to permit the center sills being made exactly identical and not one the reverse of the other. One set of rivets only is necessary for uniting the angle-pieces 38 and 44 to the center sills, as indicated in Fig. 1. The same construction is followed with reference to the angle-pieces 32 and 34, thus making a considerable saving in rivets.

The draft-sills 3 are channel-shaped sections formed, preferably, from pressed plate and have their upper flanges cut away at their inner ends, as shown at 45, and their webs lying against the inner faces of the webs of the channel center sills and riveted thereto. Their lower flanges lie underneath the center sills, as indicated in Fig. 2, and may also be riveted thereto. These draft-sills have riveted thereto the draft-lugs 46 and are connected by transverse tie-plates 47. The outer ends of the draft-sills are connected by means of angle-pieces 49 to the end sill 50. The latter is formed of pressed metal and is of general channel shape, having the top flange lying on top of and riveted to the floor-plates, said top flange being of varying width, as shown in Fig. 1. The vertical web of the end sill is provided with an opening 52 for the shank of the draw-bar and has connected thereto the draw-bar carrier 53. The car is shown as provided with a wooden drop end 55; but this is not material.

The car-frame described is very simple and strong and is composed mostly of commercial-rolled steel, only a very few special shapes being necessary.

What I claim as my invention, and desire to secure by Letters Patent, is—

1. In a metallic car, the combination with the center sill, of a body-bolster composed of an upper or tension member, a lower or compression member, web-filters between said members, said web-filters comprising channel-shaped structures placed back to back and secured to the top and bottom members and to the center sill, and vertically-arranged flanged shapes having one flange secured between the ends of said web-filters and their other flanges secured to the sides of the car.

2. In a car-underframe, the combination with the center sill, of a body-bolster composed of two channel-shaped structures placed back to back and secured to the center sill and to the car sides, and an extension-plate riveted to the lower flanges of said channel members and extending outwardly from the same to form a bracket to support the car side.

3. In a metallic car, the combination with the center sill, of a body-bolster composed of two flanged members placed back to back and united together and secured to the center sill, said members having their outer ends

spread apart, vertically - arranged flanged shapes having one flange secured between the separated ends of the bolster members, and car side plates secured to the outwardly-projecting flanges of said flanged members.

4. In a metallic car, the combination with the center sill and side plates, of a body-bolster composed of an upper or tension member, a lower or compression member, and web-fillers between said members, said web-fillers comprising channel-shaped structures placed back to back and secured to the bottom and top members and to the center sills and having their outer ends separated, vertically-arranged flanged shapes having one flange secured between the ends of said channel members and their outer flanges secured to the car sides.

5. In a metallic car, the combination with a center sill, of a body-bolster of less depth than the center sill, floor-supports extending longitudinally of the bolster and secured thereto, and a horizontal floor supported on said sill and floor-supports.

25 6. In a metallic car, the combination with the center sill, of a body-bolster of less depth than the center sill and comprising web-fillers and a top cover-plate riveted thereto, and floor-supports extending longitudinally of the bolster, said floor-supports being composed of flanged shapes secured to the bolster by the same rivets which secure the top cover-plate to the web-fillers.

35 7. In a metallic car, the combination with the center sill and car sides, of transoms or diaphragms comprising flanged shapes secured to the center sill and extending to the car sides, a continuous transverse tie member extending from side to side underneath the center sill, and strut members secured di-

rectly to both the flanged members and transverse tie member.

8. In a metallic car, the combination with a center sill and car sides, of transoms or diaphragms comprising flanged shapes secured to the center sill and extending to the car sides, a continuous transverse tie member extending from side to side underneath the center sill, and strut members connecting the flanged member and transverse tie member at intervals.

9. In a metallic car, the combination with the center sills and car sides, of transoms or diaphragms comprising flanged members secured to the center sills and to the car sides, a center brace between the center sills comprising a plate extending below the center sills, a continuous transverse member extending from side to side underneath the center sills and secured to the depending edge of the center braces, and web-plates connecting said transverse member to the flanged members.

10. In a metallic car, the combination with the longitudinal sills and car sides, of transoms or diaphragms comprising flanged members secured to the longitudinal sills and car sides, a continuous transverse member extending from side to side underneath the longitudinal sills and extending beyond the flanged members to form brackets to support the car sides, and web-plates connecting said continuous transverse member and the flanged members.

In testimony whereof I, the said JOHN M. HANSEN, have hereunto set my hand.

JOHN M. HANSEN.
